Primary Examiner — Susan Moon Lee**CLAIM**

We claim the ornamental design for a dog food reminder, as shown and described.

DESCRIPTION

FIG. 1 is a front perspective view of a dog food reminder; FIG. 2 is a Front View of a dog food reminder; FIG. 3 is an Exploded Front View thereof showing a removed container; FIG. 4 is an Exploded Right Side View thereof showing a removed container; FIG. 5 is a Rear View thereof; and, FIG. 6 is an exploded perspective view of the container component of the dog food reminder, shown separately for clarity. The left side view is a mirror image of the right side view of the dog food reminder.
